ATTORNEY

UNITED STATES PATENT OFFICE

EZRA G. PETTIT, OF CROOKSVILLE, OHIO

MOTOR

Application filed May 22, 1926. Serial No. 111,054.

The object of this invention is to provide improved means for elevating a portion of the water flowing from a spring or other source of supply.

5 A further object is to provide for a considerable fall for a portion of the water, to be conveyed to a point of discharge, and for the elevation of the remainder of the supply.

A further object is to provide an apparatus 10 including a plurality of pump cylinders and pistons, and pipe connections, the pistons operating in reverse relation, and being connected by a lever controlling an automatic three-way valve, so that when the lower cylinder 15 has been filled from the bottom, and the upper cylinder has been simultaneously filled from the top, the three-way valve will be closed on the supply side and will be opened toward a discharge or waste pipe, permitting

20 the water in the lower cylinder to pass out, and resulting in the downward movement of the piston therein and the upward movement of the upper piston, for forcing the water from the upper cylinder to a point of consumption.

25 With the foregoing and other objects in view, the invention consists in the novel construction and arrangement of elements described, illustrated and claimed, it being understood that modifications may be made 30 within the scope of the claim without departing from the spirit of the invention.

In the drawings forming part of this application:

Figure 1 is a view showing the two cylinders in vertical section and showing the remainder of the apparatus in elevation.

Figure 2 is a detail chiefly in section, showing a three-way valve adapted to be used below the lower cylinder and at the point shown 40 in Figure 1.

Figure 3 shows the valve casing of Figure 2 from the opposite side, stops for limiting the movement of the arm connected with the weight being illustrated, these stops being at 45 an angle of 90 degrees.

An upper cylinder is designated 10, this cylinder being open at the bottom, and a lower cylinder is designated 12, the cylinder last named being open at the top. Pistons 13 and 14 are positioned in the respective cylin-

ders, and piston 13 has connection by means of rod 15 with one end of lever 16, while piston 14 has connection through rod 17 with the opposite end of lever 16. This lever is mounted intermediate of the cylinders, and is shown in Figure 1 as being in horizontal position when the pistons are at points intermediate of the ends of their strokes. It will be observed that the pistons operate simultaneously in reverse relation, so far as direction is concerned, and that they move at the same time toward the closed ends of the cylinders.

Lever 16 is pivotally mounted at 18 on standard 19, supported on a suitable base 20, this base also supporting uprights, such as 21 and 22, which in turn support upper cylinder 10. The lower cylinder rests on base 20.

Extending from the upper end of cylinder 10 is a vertical pipe 24, and extending from the lower end of cylinder 12 is a vertical pipe 25, the arrows showing the direction of the flow of water therethrough.

A pipe extending from any suitable source of supply is designated 26, and communicates with pipe 24 at point 27, where a suitable form of pipe connection is illustrated. A check valve 28 prevents the return flow of water through the pipe section 29, and another check valve, designated 30, is placed in pipe 24. Pipe 26 has communication through connection 31 with pipe 32 extending downwardly and then horizontally, so that it may have connection with pipe 25, from the lower cylinder, by means of valve casing or housing 37'. Pipe 32 constitutes a supply pipe for cylinder 12 and conveys water to the lower portion thereof, below piston 14, while pipe 26 conveys water through connection 27 directly to the upper part of cylinder 10.

The three-way valve shown in Figures 1, 2 and 3 constitutes an important feature, and this element is designated 37, and the three ports of the valve member communicate, in Figure 2, with supply pipe 32, discharge or waste pipe 25, and connection 25' leading to the bottom portion of cylinder 12. The housing for valve 37 is shown at 37', and the stem 38 of the valve extends through the housing

and carries a radial arm 39 supporting on its outer end a weight 40. The limit of movement of arm 39 is represented by the stops 41 and 42, it being understood that these are on the farther side of the casing as the latter is viewed in Figure 2.

Valve stem 38 carries a gear wheel or pinion 43 meshing with a segmental rack 44 pivoted at 45 and having connection at 46 with rod 47 passing through eye member 48 on lever 16. Collars 51 and 52 on rod 47 limit relative movement between this rod and lever 16.

Water flowing through supply pipes 26 and 32 passes into the upper end of cylinder 10 and into the lower end of cylinder 12 and the movement of the pistons causes the left end of lever 16 to move downwardly and the right end to move upwardly. At the limit of movement in this direction collar 52 is engaged by eye member 48 on lever 16, and segmental rack member, or arm, 44 moves about its pivot and causes the rotation of gear wheel 43 and the rotation of valve 37, from the position of Figure 2, in a clockwise direction, as illustrated in dotted lines in Figure 1. The supply to cylinder 12 is thereby cut off from pipe 32 in Figure 2, and water is permitted to flow through connection 25', valve 37, and pipe 25 to a point of discharge. This represents the portion of water not utilized or saved for delivery to a point of consumption. When cylinder 12 has been emptied through pipe 25, the lever 16 will have tilted to a position in which piston 13 in the upper cylinder has forced the water therein outwardly through pipe 24, for delivery where desired. The check valves 28 and 30 operate in an evident manner in preventing the return of water thru connection 29 or the return of water from pipe 24 to cylinder 10.

The opening of valve 37 to the discharge pipe 25, and the passage of water from cylinder 12, decreases pressure below piston 14, and as this piston is under full atmospheric pressure from above, it will move downwardly and elevate piston 13 of cylinder 10.

Piston 13 will operate against the fluid in cylinder 10 and in pipe 24, but nevertheless if the elements of the apparatus are properly proportioned, the air pressure above piston 14 will exert sufficient lifting force on piston 13 (through the connections shown), to raise water in pipe 24 to a height not exceeding 32 feet, depending upon the degree of efficiency attained.

The length of pipe 25, or the vertical height of the water therein, determines the rate of discharge, under gravity, from that pipe, and facilitates the downward movement of piston 14 under atmospheric pressure.

Having thus described the invention, what is claimed as new, is:—

65 In a vacuum motor, a cylinder, a valve cas-

ing having a port communicating with the lower portion of the cylinder, and having a port in communication with a source of water supply, and a discharge port, a rotatable ported valve member controlling the ports of 70 the casing, a weighted arm connected with the valve, and extending radially with reference to the axis of rotation, a pivoted element and means engaged thereby for rotating the valve, a piston within the cylinder, a rod connected with the piston, a lever pivotally mounted and pivotally connected with the rod, a second rod pivotally connected with the pivoted element controlling the valve, and means carried by the second rod and lever for 80 imparting thrust to the rod, longitudinally thereof, at the approximate limit of angular movement of the lever about its pivot, and at a corresponding point in the direct movement of the piston in its cylinder, the piston 85 and lever being movable independently of the rod and valve prior to the approach of the aforesaid limit of movement thereof.

In testimony whereof I affix my signature.
